UNITED STATES PATENT OFFICE.

LUCIAN C. JACKSON, OF BUFFALO, NEW YORK.

MEANS FOR CONTROLLING EXPLOSIVE ENGINES.

1,244,737.

Specification of Letters Patent. Patented Oct. 30, 1917.

Application filed June 2, 1902. Serial No. 109,867.

To all whom it may concern:

Be it known that I, LUCIAN C. JACKSON, a citizen of the United States, and a resident of Buffalo, in the county of Erie and State of New York, have invented new and useful Means for Controlling Explosive Engines, of which the following is a specification.

My invention relates to a device for controlling the operation of an explosive engine, whereby the proper mixture may be secured and fed to the cylinder direct or other devices located between the mixing chamber and cylinder, and has for its object to promote a thorough mixing of gas and air, and to automatically regulate the feeding of the mixture to said cylinder, so as to secure a uniform speed of the engine. Another object is to simplify the construction and make a compact mechanism. Another object is to reduce the friction of the working parts and to secure an efficient coöperation of the parts. Another object is to secure a wider range of adjustment and simpler operation than of any other similar device of which I am aware. Other advantages of my invention will be fully set forth in the following description and claims.

Figure 1, is a plan view.

Fig. 2, is a longitudinal section through Fig. 1, showing one form of governing device.

Fig. 3, is a section through Fig. 1, on the line X—Y.

Fig. 4, is a section through Fig. 2, on the line X'—Y'.

Fig. 5, is a sectional detail of a modification.

Fig. 6, is a side elevation showing an engine equipped with another form of governor, for actuating my device in a slightly different manner.

1, is a casing forming a mixing chamber.

45 2, is an inlet for admitting gas to said chamber; 3, is an inlet for admitting air to said chamber, 4 is an annular sleeve rotatably mounted inside of said chamber and 5, is another annular sleeve similarly mounted.

50 These sleeves are placed in line and both bear against the wall of the casing 1. 6, is a port in the sleeve 4; 7, is a port in the sleeve 5; 8, is a handle projecting from the sleeve 4, through a slot in casing 1, whereby 55 the size of the opening through which the gas passes is controlled. 9, is a handle

attached to the sleeve 5, in a similar manner for regulating the passage of air. 10, is a sleeve valve in line with the sleeves 4, and 5, and of the same diameter, and provided 60 with ports 11; 12 and 13, are ports in the casing 1, which communicate with pipes 14 and 15, which lead to inlet valves on a double cylinder engine, or directly to the cylinder or cylinders without intermediate 65 valves as desired.

Where only one set of valves for one cylinder are supplied only one pipe as 14, may be employed, as shown in Fig. 6.

16, is a shaft driven from the engine 70 and the sleeve 10, is slidably mounted thereon. 17, is a hollow stem on the sleeve 10, into which the shaft 16 projects; 18, is a spline on shaft 16 for operating the sleeve 10. 19, is a groove on the stem 17, which is 75 engaged by a ring 20. 21 is a bell crank lever attached to the ring 20, and operated by a governor 22. The governor 22, may be driven by suitable gearing 23. 24 is an index on the casing 1, lying between handles 80 8, and 9, for indicating positions of the sleeves 4, and 5.

The sleeves 4, and 5, being suitably positioned to secure the proper relative supply of gas and air, allow the same to enter the 85 chamber. A thorough mixing results, and the mixture is allowed to pass into the pipes 14 and 15 alternately as the sleeve 10, is revolved by the engine.

Should the speed of the engine vary from 90 the point at which the governor 22, is set to operate, then the governor shifts the sleeve 10 and alters the size of the openings through the ports 13, and 12, and thus diminishes or increases the amount of mixture which passes therethrough, depending on whether the speed of the engine has respectively increased or diminished. It will be seen that the sleeves 4, and 5, may be set to give a suitable proportion of gas, 100 and air, so that combustion will be perfect, whatever the speed of the engine. Sleeve valve 10 is symmetrical in form except for its port and stem 17 and so practically balanced to any pressure of the gases, as shown 105 in Figs. 2 and 3.

In the construction shown in Fig. 2, the shaft 16 may revolve at one half the engine speed, so as to bring the ports 11 and 12 and 11 and 13 into communication at the 110 proper time.

Fig. 5, shows a construction for conduct-

ing the charge to two inlet puppet valves 30 and 31. In this construction the sleeve 10^a, which corresponds to the sleeve 10 before described, is provided with two ports 5 as shown. The valves 30 and 31 may admit the mixture to two cylinders alternately.

If desired the shaft 16 may be given a rotation independently of its normal speed as shown in Fig. 6, through the medium of a 10 fly-wheel governor. This independent rotation may reduce or increase the amount of mixture fed to the pipes 14 and 15 by varying the time of establishing communication through the ports 11 and 12, and 11 15 and 13 and regulate the speed of the engine accordingly. This governor comprises weighted arms 32, which are connected by links 33, to a spiral gear 34, which is rotatably mounted on the fly-wheel 35. 36 is 20 a spring for actuating the arms 32 against the centrifugal action of their weights. 37 is a spiral gear meshing with the spiral gear 34, and is carried by shaft 16^a. The fly-wheel rotates gear 34 and causes the shaft 25 16^a to revolve, and when the arms 32 are pivotally moved by a change of speed of the flywheel, gear 34 is rotated independently of the flywheel and thereby shaft 16^a.

It is obvious that changes may be made in 30 the particular construction shown without departing from the spirit of the invention.

What I claim is:

1. In an explosive engine, in combination with a source of fuel supply, a series of explosion cylinders, a manifold distributing chamber body common to said cylinders and between said source of fuel supply and said cylinders, said body provided with separate means of communication between the same 40 and each of said cylinders, positively operated means for opening one of said means of communication and simultaneously closing the others and means to vary the timing of the opening of said communication means.

45 2. In a device for supplying a fuel charge to the combustion chamber of a gas engine, the combination, of a cylindrical valve having a port, a port in said combustion chamber, means to operate said valve and bring 50 its port into communication with said combustion chamber port during its charge feeding stroke and means to vary the operation of said valve whereby the fuel charge to said combustion chamber is regulated.

55 3. In an internal combustion engine having a combustion chamber in combination with a source of fuel supply, a port in said combustion chamber, a cylindrical ported valve, means to constantly rotate said valve 60 and bring its port into communication with said combustion chamber port during each

rotation of said valve, means to operate said valve to regulate the fuel supply and means to vary the proportions of said fuel.

4. In a regulating device for controlling 65 the fuel supply to a gas engine the combination, of a casing having ports, a valve device in said casing and having a port adapted to register with said casing ports, means to continuously rotate said valve device and bring its port into and out of communication with said casing ports and means to vary the normal rotative movement of said valve device.

5. In a regulating device for controlling 75 the supply of air and other gases to a gas engine, the combination, of a casing having air and gas inlets and outlets, a valve device having ports adapted to simultaneously register with said outlets, means to 80 constantly rotate said valve device and bring its ports into and out of communication with said outlets and means to control the movement of said valve device, whereby the quantity of air and other gases flowing 85 to said gas engine may be varied.

6. In a means for controlling explosive engines, a regulating valve device having air and gas inlets and outlets, separate hand operated means to vary the capacity of said 90 air and gas inlets, a continuously rotating valve device having ports adapted to be brought into and out of register with said outlets, said valve device adapted to receive air and gas from said inlets and deliver same to said outlets when in register therewith and means to regulate said valve device whereby the quantity of said air and gas flowing through said outlets is controlled.

7. In a valve device for controlling the supply of air and other gases to a gas engine, the combination of a casing having an air inlet, a gas inlet and a mixture outlet, a continuously rotating valve device, 105 in the form of a hollow sleeve with a side port, receiving a mixture from said air and gas inlets and delivering the same through said port to said mixture outlet and automatic means to move said valve and thereby 110 control the quantity of the mixture delivered to the combustion chamber of a gas engine during its suction stroke.

In testimony whereof, I have signed my name to this specification in the presence 115 of two witnesses at Warren, county of Warren and State of Pennsylvania, this 30th day of April 1902.

LUCIAN C. JACKSON.
